GAS MEASURING APPARATUS

Roy C. Gauger, Rochester, N.Y., assignor to Consolidated Electrodynamics Corporation, Pasadena, Calif., a corporation of California

Application May 9, 1957, Serial No. 658,206

6 Claims. (Cl. 313—7)

This invention relates to electronic tubes, and more particularly to a gas discharge tube such as the cold cathode gas discharge tube used to measure gas pressures.

The invention is described herein as applied to a cold cathode discharge tube such as that described in Patent No. 2,745,059, issued May 8, 1956, to R. C. Gauger. However, various features of my improved device are applicable not only to cold cathode gas discharge tubes, but also to other types of gas discharge tubes and in some respects to electronic tubes in general.

The cold cathode gas discharge device for measuring gas pressures described in Patent No. 2,745,059 includes an umbrella shield attached to a ceramic insulator disposed within an envelope about the lower part of a lead-in wire to the anode. This umbrella shield satisfactorily protects the body of the ceramic insulator from sputtered metallic material which could, after some period of operation, bridge the insulator with a conductive coating and cause the tube to become inoperable. However, coating of the insulator with the sputtered material, even though it is not great enough to bridge the insulator, may interfere with the proper operation of the tube after long periods of time. Thus, the metallic material removed from the electrodes and deposited on the adjacent ceramic insulator may increase the effective area of the anode, requiring a change of calibration in the system in which the tube is utilized.

The present invention discloses improvements that overcome the foregoing difficulty and also afford additional advantages in vacuum tube construction. Thus, in accordance with my invention I provide a tube having at least two primary electrodes spaced from each other in an envelope and an auxiliary electrode having an orifice therein. A conductive lead to one of the electrodes, e.g. an anode, passes through the orifice but is spaced from the walls thereof by an annular gap, preferably much longer than it is wide. The auxiliary electrode itself is connected to another of the primary electrodes, e.g. a cathode. Preferably the width of the annular gap is less than the spacing between the electrodes in the envelope.

A cold cathode gas discharge tube incorporating the improvement just described will continue to conduct current when the pressure of gas within the tube rises to a high value, so that the current flow through the tube can be used to operate external circuitry, e.g. a relay, when the higher pressure prevails. By way of example, a conventional cold cathode discharge tube conducts current only when the pressure within it is below about 25 mm. Hg. Above this pressure, discharge is extinguished. In contrast, such a cold cathode discharge tube modified to include the auxiliary electrode arrangement just described continues to operate as the pressure rises to atmospheric levels (760 mm. Hg), because as pressure is increased the discharge transfers to the annular gap between the lead and the auxiliary electrode and continues to pass current in the form of an arc or spark.

In my preferred tube structure, the orifice or bore in the auxiliary electrode communicates with a chamber out-

2

side the envelope of the tube. This chamber is sealed from the atmosphere. A cup-shaped insulating bushing forms at least a part of the wall of this chamber and the conductive lead passes through a seal in this cup. In a cold cathode discharge tube modified to include the features just described, discharge takes place between the primary electrodes in the envelope while the tube is functioning at low pressure. The mean free paths of the ions formed in the discharge are so long that the ions are unable to pass through the relatively long narrow gap in the auxiliary electrode. Hence, metallic deposits in the gap are minimized. At the same time, the cup-shaped insulator which forms part of the wall of the outside chamber is protected from metallic deposits. In consequence, no change occurs in the effective electrode area to require a change in calibration and the insulator is protected more effectively from short circuits.

Assembly and disassembly of tubes constructed in accordance with my invention are greatly facilitated if the primary electrode, e.g. the anode, the attaching lead, the auxiliary electrode, and the cup-shaped insulator form a unitary structure held in an electrode insert opening in the envelope, for example by a threaded retainer.

These and other aspects of the invention will be understood thoroughly in the light of the following detailed description of a presently preferred embodiment. The description is illustrated by the accompanying drawings, in which:

Fig. 1 is a sectional elevational view showing a preferred embodiment of my new invention in a cold cathode gas discharge device; and

Fig. 2 is a fragmentary sectional view taken along line 2—2 of Fig. 1.

The drawings show a cold cathode discharge tube 10 provided with an elongated envelope 12 of conductive material. This envelope has a gas inlet 14 formed at one end thereof, permitting the gas discharge tube to be attached to a gas pressure source (not shown).

The tube has a first cathode 16 and a second cathode 18 diametrically disposed within the wall of the conductive envelope 12. Disposed in the space between the two cathodes and along the axis of the conductive envelope is an anode 20. This anode is in the form of a loop. The cathodes are tapered toward the anode and have plane surfaces 16A, 18A substantially parallel with the plane of the loop anode (see Fig. 2).

When gases enter the area within the envelope, electrons from the cathodes are attracted toward the anode. As they proceed toward the anode, collisions with the gas molecules occur, providing positive ions which then flow toward the cathodes. The longer the path followed by the electrons from the cathodes, the more chance of collision with gas molecules. To increase the path of the electrons from the cathodes to the anode, a magnet 22 of substantially annular shape is disposed adjacent the cathodes. The field produced by the magnet tends to direct the electrons from the cathodes away from the anode. This causes the electrons to follow a helical path to the anode. As the path of the electrons is thus increased, there is opportunity for more collisions with the gas molecules.

An insulator housing 24 of flexible rubber encloses the cathodes, the magnet, and an annular stiffener 26.

The lower portion of the conductive envelope is provided with a bore 28 of reduced diameter. This bore is sufficiently large to permit the insertion and removal of the anode from the envelope.

A conductive bushing or auxiliary electrode 30 is releasably clamped to the lower portion of the envelope. This bushing is of a substantially cylindrical shape and includes a hub portion 32 which extends into the bore. A long narrow orifice extends entirely through the body

and hub portion of the conductive bushing. This orifice is of larger diameter than a conductive lead 34 which extends through the orifice and is connected to and supports the anode. Thus there is an annular gap 36 separating the wall of the orifice from the conductive lead.

The conductive lead is in sealed connection with an insulator 38. This insulator is cup-shaped. Its upper rim is connected to a conductive sleeve 40, which in turn is connected to the lower portion of the conductive bushing. The bushing, sleeve and insulator thus define an auxiliary chamber 42. A by-pass bore 44 in the bushing connects the interior of the envelope with the auxiliary chamber and aids in pumping out the latter.

In the structure just described, the cup-shaped insulator is outside the envelope 12 and metallic materials resulting from sputtering will not be deposited on it.

The anode, lead, cup-shaped insulator 38, conductive sleeve and conductive bushing are connected together in a unitary structure and constitute the anode assembly. This may be removed as a unit for examination and repair. To this end, the lower end of the envelope is threaded to accommodate a threaded cup-shaped retainer 46. There is a hole 48 in the bottom of the retainer. The diameter of the hole is greater than the diameter of the cup-shaped insulator 38 but less than the diameter of conductive bushing. Hence, the retainer may be unscrewed and removed over the insulator. The anode assembly can then be removed.

Conversely, the anode assembly is replaced by inserting the anode and placing a locating pin 50 in a recess formed in the conductive bushing. The retainer is then replaced over the insulator 38 and screwed upon the envelope, with the lower portion of the retainer pressing against the conductive bushing. A gasket 52 is located in a groove formed in the envelope to provide for seal-tight engagement.

In operation, when the tube is functioning at low pressures, it continues to conduct current by ionization of the gases within the envelope. The ionization takes place primarily in the space between the cathodes and the anode. As the pressure is increased, the discharge transfers to the gap between the conductive bushing and the lead continues to pass current in the form of an arc or spark. The improved model will continue to operate up to atmospheric pressure, thus permitting the use of the tubes in applications where an auxiliary relay is used to operate external circuitry at some level above a chosen pressure limit.

When discharge takes place in the space surrounding the anode loop during operation at low pressures, some ions tend to travel to the inside surfaces of the envelope, but are unable to pass through the relatively long gap in the conductive bushing. Thus, metallic deposits on the cup-shaped insulator are reduced to a minimum. When operated at higher pressures, so that the conductive bushing operates as an auxiliary electrode, the mean free paths of the ions are so small that ions are again unable to reach the surface of the insulator 38.

I claim:

1. In an apparatus for measuring gases the combination comprising an envelope defining a gas discharge space, first and second primary electrodes, means for supporting the second electrode within the envelope, insulating means secured between one end of the envelope and the first electrode for supporting the first electrode within the envelope and in spaced relation to the second electrode, an auxiliary discharge electrode surrounding at least a portion of the first electrode and disposed between the insulating means and the gas discharge space, the auxiliary electrode being electrically coupled to the second electrode and being radially spaced from the first electrode to impede the movement of ions in a substantially annular gap formed between the first and auxiliary electrodes to thereby substantially prevent ions from the gas discharge space from reaching the insulating

means and producing a metallic deposit on the insulating means.

2. In an electronic device for measuring gases including an envelope defining a gas discharge space, first and second primary electrodes and means for supporting said electrodes within said envelope, the means for supporting the first electrode including insulating means secured between one end of the envelope and the first electrode, the improvement comprising an auxiliary electrode providing an arc discharge path for said first electrode including electrically conductive means substantially surrounding a portion of said first electrode and disposed between the insulating means and the gas discharge space, the auxiliary electrode being spaced from said first electrode to form a long and narrow annular arc gap impeding the movement of ions through said gap to thereby substantially prevent ions from the gas discharge space from reaching the insulating means.

3. In a gas discharge device for measuring the pressure of gases including an envelope defining a gas discharge space, an anode, a cathode and means for supporting said anode and cathode in spaced relation to provide for gas discharge at low gas pressures, the improvement comprising an auxiliary discharge electrode annularly disposed about a portion of said anode and proximate thereto for producing an arc discharge at higher gas pressures extinguishing the gas discharge between the anode and cathode.

4. In gas discharge devices for measuring the pressure of gases including an envelope defining a gas discharge space, and means producing a discharge in said space including an anode and cathode and means for supporting said anode and cathode in spaced relation within said envelope, the means for supporting the anode including insulating means secured between one end of the envelope and the anode, the improvement comprising arc discharge means including an annular auxiliary electrode connected to said cathode and disposed between the insulating means and the gas discharge space, the auxiliary electrode being spaced radially about a portion of said anode to provide an arc gap between said anode and auxiliary electrode which is less than the space between said anode and cathode to thereby substantially prevent ions from the gas discharge space from reaching the insulating means.

5. In gas discharge devices for measuring the properties of gases including an envelope defining the gas discharge area and first and second primary electrodes of opposite polarities supporting within said envelope, the improvement comprising arc discharge means for measuring properties of gases outside the range of gas discharge including an auxiliary electrode connected to said second electrode, said auxiliary electrode substantially surrounding a portion of said first electrode and spaced radially therefrom to provide an arc gap between the first and auxiliary electrodes which is smaller than the mean free path of ions formed in the gas discharge area, and annular enclosure means secured to the auxiliary and first electrode to provide a sealed chamber outside of said envelope opening into said arc gap, said enclosure means being formed at least partially of material insulating said first electrode from said auxiliary electrode.

6. In a cold cathode gas discharge tube for measuring properties of gases at low pressures including an elongated envelope having at least one open end and defining the gas discharge area, an anode, a pair of cathodes, and means for supporting said cathodes on diametrically opposite sides of said envelope, the improvement comprising arc discharge means for continuing conduction at gas pressures sustaining gaseous discharge including an annular auxiliary electrode having an aperture connected to at least one cathode and disposed at one end of said envelope, said electrode surrounding a portion of said anode and spaced radially from said portion to form a long narrow annular arc gap blocking passage of ions through said gap, means for forming a sealed enclosure

5

opening into said aperture including a cup-shaped bushing surrounding the outer end of said aperture, said bushing being composed partially of insulating material surrounding a portion of said anode outside the envelope, and means for releasably sealing the opening in the end of said envelope including clamping means having an aperture passing a portion of said anode outside the envelope and the sealed enclosure, lateral flanges

6

seating against transverse edges of said auxiliary electrode, and a clamping portion releasably securing to the adjacent lateral sides of the open end of said envelope.
